[57] CLAIM

The ornamental design for a colliding ball toy, as shown.

DESCRIPTION

FIG. 1 is a perspective view of a colliding ball toy showing my new design;

FIG. 2 is a side elevational view thereof;

FIG. 3 is a front elevational view thereof; and

FIG. 4 is a rear elevational view thereof.

The tethered members in FIGS. 3 and 4 are shown fragmented for ease of illustration.

FIG. 1

FIG. 2

FIG. 3

FIG. 4
